UNITED STATES PATENT OFFICE.

FREDERICK S. DENISON, OF MINNEAPOLIS, MINNESOTA, ASSIGNOR TO MINNEAPOLIS
HEAT REGULATOR COMPANY, OF MINNEAPOLIS, MINNESOTA, A CORPORATION OF
MINNESOTA.

IGNITION-CONTROLLING MEANS.

Application filed November 27, 1922. Serial No. 603,588.

This invention relates to improvements in means for the control of ignition such, for example, as that provided by a spark-plug. Such control is particularly useful in conjunction with heating plans of the oil-burning type now in common use in the heating of buildings.

It is common in such installations to employ a pilot light of gas furnished from the usual commercial city mains or otherwise, such light being adapted to ignite the vaporized fuel when the supply thereof is turned on. In place of such a pilot light a spark plug may be employed for ignition purposes and it is desirable that the spark plug should be energized to provide the necessary sparking during an appreciable interval in order to assure ignition of the fuel charge presented adjacent thereto. By the employment of this novel invention, the spark-plug may be energized for a predetermined period after which it ceases, such period being of sufficient duration to assure the desired ignition.

The object therefore of this invention is to provide an improved ignition controlling means.

Other objects of the invention will more fully appear from the following description and the accompanying drawings and will be pointed out in the annexed claims.

In the drawings, there has been disclosed a structure designed to carry out the objects of the invention but it is to be understood that the invention is not confined to the exact features shown as various changes may be made within the scope of the claims which follow.

In the drawings:

Figure 1 is a longitudinal sectional view of the solenoid-controlling device for the spark-plug switch;

Figure 2 is a view in side elevation thereof with part broken away to show the device in closing position;

Figure 3 is a sectional plan view of the device on the line 3—3 of Figure 2.

Figure 4 is a sectional detail view of the switch contacts on the line 4—4 of Figure 3;

Figure 5 is a wiring diagram showing the device adapted for operation with a thermostatically controlled heating plant.

This present selected embodiment of the

invention is shown for purposes of explanation, in conjunction with a thermostatically controlled heating plant. The novel features of such an indicated installation (with the exception of the present ignition control) form the subject-matter of a prior co-pending application by the inventor hereof, Serial No. 580,360, filed August 7, 1922, while the use of a common form of spark-plug for ignition purposes is shown in the prior co-pending application of Harold W. Sweatt, Serial Number 580,344, filed August 7, 1922. In the last-mentioned application, the spark-plug is constantly energized during the operation of the usual blower-motor. In this present invention, however, the spark-plug is only energized for a predetermined interval as above noted.

Broadly, this invention is directed to the employment of a spark-plug with a circuit to supply electric energy thereto and with a switch interposed in the circuit to open and close it. This switch has a movable contact and a fixed contact which are arranged normally to remain in circuit-closing position. A detent is provided normally to hold the contacts in circuit-opening position to prevent energization of the spark-plug and means are provided momentarily to release the contacts to permit circuit-closing and to return them to circuit-opening position after a predetermined interval which assures proper ignition of a fuel. While such ignition-controlling means may be manually actuable, it is preferred automatically to cause this controlling means to function, as by means of a thermostat. Such automatic functioning may be described in connection with a wiring diagram (Figure 5) after the structure and operation of this device itself has been explained.

The spark-plug 6 of any present form, is provided with two conductors 7 and 8 connecting it with the high tension side of a transformer 9, the low tension side of which has a conductor 11 connected to the lead 12 of the supply circuit to the motor 13. The lead 14 of this supply circuit has a conductor 15 connected thereto which is in electrical connection with the post 16 of the arched metallic strip 17 which forms the relatively fixed contact of a switch adapted to open and close the spark-plug circuit. The relatively

movable contact of this switch is provided by the button 18 secured to the metallic spring 19 and mounted yieldably to hold the contact button 18 against the under face of 5 the arched strip whereby the spark-plug circuit is closed. The conductor 21 leads from the other side of the low tension winding of the transformer to a post 22 in electrical connection with the spring 19 and therefore 10 with the contact button 18. While the contacts are thus yieldably urged toward a circuit-closing position, means are employed normally to detain the contacts, or one of them, in circuit-opening position. Such is 15 the function of an annular boss 23 terminally carried on the upper end of the reduced portion 24 of a metallic plunger 25 mounted for reciprocable movement. This plunger is of metal and is terminally bored to receive the 20 screw 26 in threaded engagement therein whereby the boss 23 is held in its operative position so that upon descent it may engage and depress the outer end of the spring 19 and remove the contact button 18 from the 25 strip 17 and thus break the spark-plug circuit. The plunger and boss are shown in such descended circuit-opening position in Figure 1. While any suitable tension means may be employed to maintain the plunger 30 normally in its descended position, it is found convenient to employ the tension of gravity for this purpose.

The plunger 25 is mounted to reciprocate within a cylinder 27 which, in conjunction with the plunger and associated parts, functions substantially as a dash-pot for damping the descent of the plunger after raising. It is this damped descent of the plunger which provides the desired time interval during 40 which the spark-plug circuit may remain closed. The lower end of the cylinder is closed by means of the screw plug 28, threaded to the lower cylinder end. The lower portion of the cylinder is filled with a fluid, such as oil 29 to provide the damping function. The lower portion of the plunger 25 is reduced to form a stem 31 terminating in 45 forks 32 integral with an open ended sleeve 33. The lower edge of this sleeve forms an annular valve seat for the valve 34 having an integral stem 35 slidably borne in the cylindrical hub 36 held by a plurality of radial integral arms 37 to the sleeve. The stem 35 projects above the hub 36 and has a collar 38 pinned thereto and a compression spring 39 is held upon the stem between the collar and the upper end of the hub. This spring yieldably holds the valve 34 in seated position. When ascent of the plunger occurs, the oil above the valved sleeve opens the valve 34 and permits the sleeve freely to pass through the oil. But, subsequent descent of the plunger is retarded as the valve 50 tensionably resumes seated position and oil 55 displaced by plunger descent must pass

through a by-pass 40, provided on one side of the cylinder casting, upwardly into the cylinder above the descending sleeve. The rate of flow of fluid through this by-pass and therefore the length of the time required for 70 plunger descent, may be adjustably predetermined by means of the needle 41 adapted adjustably to constrict the by-pass 40. This needle 41 is carried by a screw 42 received in threaded engagement within a counter-bored aperture leading to the by-pass. 75

Means are provided to raise the plunger from its normal circuit-opening position shown in Figure 1 to its ascended position in Figure 2 wherein the movable spring-carried contact button 18 is in circuit-closing engagement with the strip 17. While such plunger-raising may be otherwise effected, the preferred means is by way of a solenoid. The solenoid 43 is preferably mounted upon 85 the reduced portion of the cylinder 27 adjacent its upper end so that the plunger 25 may function as an armature. The reduced upper portion 44 of the metallic cylinder forms a lining for the solenoid and is closed 90 at its upper end by means of the bearing cap 45 received in threaded engagement upon the upper end of this reduced portion of the cylinder. Preferably an air vent 46 is bored in the bearing cap 45 to permit escape of air 95 and to avoid any cushioning effect upon upward travel of the plunger. When the solenoid 43 is energized, the armature plunger 25 will be upwardly drawn to permit the contact button 18 tensionably to effect electrical engagement with the strip 17. Upon the de-energization of the solenoid the armature-plunger tensionably (as here shown by force of gravity) returns to normal descended position, such descent being retarded by 105 the dash-pot function of the device.

In this preferred installation, as shown by the wiring diagram Figure 5, the solenoid is energized only momentarily. This momentary energization is conveniently effected by 110 the apparatus shown in this inventor's above-mentioned prior application. Such apparatus may now be described in conjunction with the diagram Figure 5 but without going into greater detail than is necessary to explain such use of the present invention. 115

Broadly, Figure 5 discloses a liquid fuel burner installation of the type employing a motor 13 adapted to drive a blower 47 to deliver air under pressure to a burner 48 around the open end of a liquid fuel supply pipe so that the liquid fuel may be vaporized and forcibly blown against the overhead target 49 and adjacent the spark-plug 6. The control of the motor and spark-plug circuits are so inter-related that, when the motor circuit is closed, the spark-plug circuit is closed, but the latter is opened again after a predetermined interval as above described. Furthermore, both of these two circuits are 120 125 130

automatically opened by thermostatic means, while the motor circuit is also closed thermostatically.

- The thermostatic control of the motor may 5 first be explained and thereafter the control of the spark-plug circuit. Generally considered, there is provided a switch having a pair of spaced terminals and a circuit-closer 10 cooperable therewith to complete a circuit through such terminals. This circuit-closer is preferably operable by means of an electric current operating through an armature and solenoids of opposite polarity. Means are provided singly to energize the solenoid 15 coils so that the armature may be moved in a direction to effect the desired opening or closing of the switch. The means here shown for singly energizing the coils is a thermostatic device.
- 20 The lead 12 of the motor 13 is directly connected to the side 51 of the main line circuit while the lead 14 of the motor is connected to the other side 52 of the main line through a circuit-closer 53 and its spaced blades 50. 25 This circuit-closer is shown in Figure 5 in closed position but is adapted to be upwardly rocked to open the motor circuit.

A convenient mode of rocking this circuit-closer both out of and into circuit-closing position is provided by means of the rock-shaft 54 which carries the circuit-closer 53. This rock-shaft is adapted to be rocked by an armature 55 reciprocably mounted within the alined cores of two solenoids which are 35 adapted singly to be energized to produce opposite polarity so that the armature may be selectively moved in opposite directions. One solenoid may be referred to as the upper or circuit-closing coil 56 and the other, as 40 the lower or circuit-opening coil 57.

The selective energization of these two coils is effected, in this apparatus, by means of a thermostat. Each coil is provided with a circuit leading to a suitable source of electric 45 energy and each such coil-circuit is adapted to be electromagnetically closed or opened by the thermostat and the parts are so arranged that the upper or circuit-closing coil is energized by the cold side of a thermostat circuit while the lower or circuit-opening coil is energized by the hot side of the thermostatic circuit.

Each coil is provided with a circuit connected to the main line. The lower coil 57 has a wire 58 leading from the top of its winding to a contact blade 59 insulated from a complementary contact blade 61 having a wire 62 connected to the lead 14 of the motor circuit. The lower coil also has a wire 63 leading from the bottom of its winding to a contact 64 projecting for circuit-closing engagement below a movable armature contact 65 operable to make-and-break this lower coil circuit. This armature-contact 65 is normally yieldably held out of engage-

ment with the contact 64 by any suitable means. The armature-contact 65 is provided with a wire 66 in electrical connection with the lead 12 of the motor. An electro-magnet 67 is positioned beneath the armature-contact 65 and is adapted, upon energization by the hot side of the thermostat, to break indirectly the motor circuit, as later described. Thus, the lower coil 57 is provided with its circuit which may not only 75 be opened and closed by means of an armature at one point but also may be opened and closed at another point across the blades 59 and 61. The closure of this latter break is by means of a circuit-closer 68 carried by 80 the rock-shaft 54 and operable thereby. This circuit-closer 68 is thus co-operable with the motor circuit closer 53.

The upper coil 56 has a wire 69 leading from the bottom of its winding to a contact 85 71 projecting for circuit-closing engagement below a movable armature-contact 72 operably to make-and-break this upper coil circuit. This armature-contact 72 is normally and yieldably held out of engagement with 90 the contact 71 by any suitable means.

The armature-contact 72 is electrically connected by the wire 73 to the lead 12 of the motor circuit. An electro-magnet 74 is positioned below the armature-contact 72 95 in order, upon energization, to draw the contact 72 to the contact 71 to close the coil circuit across this break. The electromagnet 74 is adapted to be energized by the cold side of the thermostat in order indirectly to start 100 the motor and, it may be noted in passing, that the spark-plug circuit is adapted to be closed when the circuit through this upper coil 56 is closed. The wire 75 leads from the upper portion of the coil 56 to the knife 105 blade 76 electrically insulated from the complementary knife blade 77 connected by the wire 78 to the main line 52. The break across the blades 76 and 77 is adapted to be closed by a circuit-closer 79, carried, similarly to the circuit-closer 68, by the rock-shaft 54. This circuit-closer 79 is here shown in dotted lines in order to indicate 110 that it is not in circuit-closing position because the circuit-closer 68 is so shown, it 115 being understood that these circuit-closers are oppositely moved. That is, when circuit-closer 68 is in closing position, the circuit-closer 79 is in circuit-opening position and vice versa.

The electromagnets 67 and 74 are adapted to be selectively energized, preferably by a thermostatic circuit. Such circuit may derive its electric energy from the motor circuit through the transformer 81. The thermostatic circuit comprises the usual hot and cold sides with thermo-bar connection. Such a thermostat is diagrammatically represented in Figure 5, wherein the usual thermo-bar 82 is electrically connected to the sec- 120 125 130

ondary winding of the transformer by means of the wire 83. The hot contact 84 has a wire 85 terminating in the knife blade 86 which is insulated from its complementary 5 knife blade 87 having a wire 88 running to the upper portion of the winding of the electromagnet 67 while the wire 89 runs from the lower portion thereof to the secondary or low-tension side of the transformer 81.

10 The cold side contact 91 is connected by the wire 92 to the knife blade 93 similarly insulated from its complementary knife blade 94 which in turn is connected by the wire 95 to the upper portion of the winding 15 of the electromagnet 74 having its lower portion thereof electrically connected by the wire 96 to the wire 89 of the secondary or low-tension side of the transformer 81. Circuit-closers 97 and 98 are carried upon the 20 rock-shaft 54 and are similar in construction and operation to the circuit-closers 68 and 79 carried at the opposite end of the rock-shaft.

Before describing the incorporation of the 25 spark-plug circuit in this apparatus, the operation of the above parts may be first explained.

In the position of the parts in Figure 5, the apparatus is shown in position wherein 30 the thermo-bar 82 has previously been bent by room temperature to cause electrical contact with the hot side contact 84, whereby current may flow from the secondary winding of the transformer 81, through the presented circuit, as follows: wire 83, thermo-bar 82, hot contact 84, wire 85, blade 86, circuit-closer 97, blade 87, wire 88, electromagnet 67, wire 89, and back to the secondary winding. The electromagnet 67 is thus 35 energized with the result that the armature-contact 65 is downwardly pulled to effect electrical connection with the contact 64 whereby the following circuit is closed: lead 12, wire 66, armature-contact 65, contact 64, 40 wire 63, opening-coil 57, wire 58, blade 59, circuit-closer 68, blade 61 and wire 62 to the other lead 14. Thus, the lower opening coil 57 is energized with the result that the armature 55 is inwardly pulled, the shaft 45 54 rocked and the circuit-closer 53 is raised to break the lead 14 of the motor circuit at the spaced insulated blades 50. The motor circuit is thus thermostatically opened resulting in cessation of the motor, blower, and 50 burner functions.

The parts are re-set automatically for a 55 call for heat by the cooling thermo-bar. As the rock-shaft raises the thermostatic circuit-closer 97, and coil circuit-closer 68, their complementary circuit-closers 98 and 79, respectively, are moved to engage and close the breaks across the blades 93-94 and the blades 76-77. Thus, when the thermo-bar bends to engage the cold contact 91, another 60 circuit is closed from the secondary winding

of the transformer 81, through the thermo-bar contact 91, wire 92, blade 93, circuit-closer 98, blade 94, wire 95, electromagnet 74, wire 96 to the secondary winding. The electromagnet 74 is thereby energized to attract the armature contact 72 to close with the contact 71 whereby a circuit is presented from the main line side 51, motor lead 12, wire 73, armature-contact 72, contact 71, wire 69, closing coil 56, wire 75, blade 76, 70 circuit-closer 79, blade 77, wire 78 to the other main line side 52. The closing coil 56 is thus energized, the rock-shaft returned to the full-line position in Figure 5 and the motor circuit closed, and the motor, blower, 75 and burner function.

Turning now to the incorporation of the spark-plug circuit in this apparatus, it may be noted that, when the rock-shaft 54 is returned to its Figure 5 position, the circuit-closers 97 and 68 are likewise returned to the indicated closed position, while the circuit-closer 79 is simultaneously moved by the rock-shaft to open position so that the circuit through the closing coil 56 is opened. 80 Thus, by connecting the solenoid 43 with the circuit of this coil 56, the solenoid 43 may be energized when the coil 56 is energized to start the motor. To this end, a wire 99 is connected to the coil wire 69 and to the 85 winding of the solenoid 43. The other end of this winding is connected by the wire 101 to the motor lead 14. Thus, coincident with energization of the motor-starting coil 56, the solenoid 43 will be energized. Furthermore, as such energization of the coil 56 is only momentary (because its circuit is immediately opened by the circuit-closer 79) so also, the energization of the solenoid is 90 only momentary. Such momentary energization of the solenoid is sufficient to elevate the plunger 24 so that upon immediate de-energization, its timed descent may commence. As before described, plunger-elevation completes the spark-plug circuit so that 95 the spark-plug functions as the motor starts and is so maintained until the predetermined interval of plunger descent has expired and the plunger has again resumed its normal 100 position interrupting the spark-plug circuit. 110

I claim as my invention:

1. Ignition-controlling means including a spark-plug, a circuit therefor connected to a source of electric energy, a switch interposed in said circuit and adapted to open and close the same, said switch having a relatively fixed and a relatively movable contact, means tending to maintain the contacts in closed position, means normally to detain the contacts in open position, and means momentarily automatically operable to close the contacts and to permit return of said contacts to open position after a predetermined interval whereby the spark-plug functions during said interval. 115

2. Ignition-controlling means including a spark-plug, a circuit therefor connected to a source of electric energy, a switch interposed in said circuit and adapted to open and close the same, said switch having a relatively fixed and a relatively movable contact, means tending to maintain the contacts in closed position, means normally to detain the contacts in open position, means momentarily operable to close the contacts and to return said contacts to open position after a predetermined interval whereby the spark-plug functions during said interval, and means adjustably to alter said interval.
- 5 3. Ignition-controlling means including a spark-plug, a circuit therefor connected to a source of electric energy, a switch interposed in said circuit and adapted to open and close the same, said switch having a relatively fixed and a relatively movable contact, means tending to maintain the contacts in closed position, a detent adapted normally to detain the contacts in open position, means momentarily operable to release said detent, and means to cause the detent to return said contacts to open position after a predetermined interval whereby the spark-plug functions during said interval.
- 10 4. Ignition-controlling means including a spark-plug, a circuit therefor connected to a source of electric energy, a switch interposed in said circuit and adapted to open and close the same, said switch having a relatively fixed and a relatively movable contact, means tending to maintain the contacts in closed position, a member adapted normally to maintain the contacts in open position, a solenoid adapted upon momentary energization to permit the contacts to assume closed position, means automatically to cause a momentary energization of the solenoid and means operable to return said contacts to open position after a predetermined interval.
- 15 5. Ignition-controlling means including a spark-plug and an electric circuit therefor, a switch in the circuit and adapted to open and close the same, the switch having a relatively fixed and a relatively movable contact, a device tending to maintain the contacts closed, mechanism to engage said device and to maintain the contacts in normal open position, means to disengage said mechanism and device to permit contact-closure, means automatically operable to return said mechanism to device engaging position after a predetermined interval, and means to regulate the length of said interval of return.
- 20 6. Ignition controlling means including a spark plug and electric circuit therefor, a switch and circuit having a relatively fixed and a relatively movable contact, the latter tending to maintain a certain position, mechanism to abut said movable contact and maintain it normally in one position, and means to cause said mechanism to release said movable contact.
- 25 7. Ignition controlling means including a spark plug, and an electric circuit therefor, a switch and circuit having a relatively fixed and a relatively movable contact, the latter tending to maintain a certain position, mechanism to abut said movable contact and maintain it normally in one position, and means automatically operable to release the contact-abutting mechanism, at the end of a predetermined interval.
- 30 In witness whereof, I have hereunto set my hand this 15th day of November, 1922.
